United States Patent Office.

S. R. WILMOT, OF BRIDGEPORT, CONNECTICUT.

Letters Patent No. 84,040, dated November 10, 1868.

IMPROVED APPARATUS FOR SIZING GLASS CYLINDERS.

The Schedule referred to in these Letters Patent and making part of the same.

To all whom it may concern:

Be it known that I, S. R. WILMOT, of Bridgeport, in the county of Fairfield, and State of Connecticut, have invented a new Improvement in Apparatus for Sizing Glass Cylinders; and I do hereby declare the following, when taken in connection with the accompanying drawings, and the letters of reference marked thereon, to be a full, clear, and exact description of the same, and which said drawings constitute part of this specification and represent, in—

Figure 1, a top view,

Figure 2, a side view, and in

Figure 3, a vertical central section.

This invention is designed as an aid in the manufacture of glass cylinders, the object being to form the cylinders of identically the same diameter as each other, designed more particularly for the manufacture of lamp-chimneys.

In some classes of burners, it is essential that the base of the chimneys be all of the same diameter; especially is this the case in the "sun-burners," where the glass is held by springs upon the inside. In the usual manner of forming the chimney, it is impossible to make the chimneys uniformly round and of the same diameter.

By my invention, the base of the chimneys are all of the same size, and perfectly round in form, or, if not round, uniformly of the same shape; and the invention consists in the arrangement of several fingers, over which the base of the hot chimney is set, the fingers extending up into the chimney, and arranged so that, by the operation of a cam or similar device, the several fingers are simultaneously spread or opened within the chimney, expanding the chimney to the size required, the said fingers being adjusted for the purpose.

To enable others to fully understand my improvement, I will describe the same as illustrated in the accompanying drawings.

A is the base, set or formed upon a plate, B, the said base being of larger diameter than the chimney or cylinder to be sized. The said base is grooved or constructed so as to receive several fingers, *a*, more or less in number, which I prefer to secure therein by a spring or ring of rubber, C, around the base and fingers, as seen in figs. 2 and 3, the tendency of which is to force the upper end of the fingers inward, as in fig. 2.

At a convenient point between the fingers I arrange a cam, D, constructed so that, by turning or moving the said cam, the fingers are acted upon simultaneously, to be thrown out, as denoted in red, fig. 3, shown here

as being moved by a lever, E, connected to the cam D by a shaft, F, as seen in fig. 3.

The chimney to be sized is, when in the proper state, placed over the fingers, as denoted in fig. 3; then, by turning the lever, the fingers expand, as denoted in red, and stretch or expand the chimney to the required size, the size being adjusted by a set-screw, G, which arrests the movement of the lever, or by other convenient device; therefore chimneys or cylinders are successively made, and positively brought to the same size and form.

I have represented the fingers as arranged for a round chimney, but it will be readily seen that other forms, as elliptical, may be sized in the same manner, by arranging the fingers accordingly. It will also be seen that various devices may be employed for operating the fingers.

Though designed to operate upon the inside of the cylinder, the same result may be accomplished by arranging the fingers so as to receive the cylinder between them, and contract the glass by pressure upon the outside. This may be accomplished by simply reversing the operation of the cam and spring, the spring to throw open the fingers, and the cam operating to close them.

In the use of the fingers as shown, the surface of the cylinder will be a series of flat surfaces, corresponding to the number of fingers. Should this be objectionable, I place around the fingers a divided band of thin steel, or any suitable metal, the fingers operating within the band, to expand and force the band outward, which will press evenly upon the inner surface of the glass, and consequently produce an even surface on the glass; or, to size the outer side of the cylinder, the band may be placed inside the fingers and contracted.

A bead, or other irregularity, may be formed upon the surface, by constructing the fingers with the necessary projections or recesses on the fingers.

Having fully described my invention,

What I claim as new and useful, and desire to secure by Letters Patent, is—

The arrangement of the several fingers *a*, operated so as to size the cylinders, by opening the said fingers upon the inside, or closing them upon the outside of the said cylinder, substantially as set forth.

S. R. WILMOT.
